UNITED STATES PATENT OFFICE.

WILSON HOUSMAN, OF ELKHART, INDIANA.

SPARK-PLUG.

1,301,562.

Specification of Letters Patent. Patented Apr. 22, 1919.

Application filed November 26, 1917. Serial No. 204,048.

To all whom it may concern:

Be it known that I, WILSON HOUSMAN, a citizen of the United States, residing at Elkhart, in the county of Elkhart and State of Indiana, have invented certain new and useful Improvements in Spark-Plugs, of which the following is a specification.

This invention relates to spark plugs for internal combustion engines, the primary object of the invention being to provide a plug embodying means for relatively adjusting and centering the central and outer electrodes, to compensate for wear due to the sparking action and for any variation from the normal in the position of the points due to the outer electrode being bent or otherwise moved out of position.

A further object of the invention is to provide a spark plug in which a movable tip for the outer electrode is provided to increase the area thereof and to keep the same free from carbon or other deposits.

The invention consists of the features of construction, combination and arrangement of parts, hereinafter fully described and claimed, reference being had to the accompanying drawing, in which:—

Figure 1 is a vertical longitudinal section through a spark plug embodying my invention.

Fig. 2 is a horizontal transverse section on the line 2—2 of Fig. 1.

Fig. 3 is a sectional perspective view of the movable cap or sleeve upon the outer electrode.

The spark plug 1 may be of any ordinary general construction, and is shown in the present instance as comprising a core 2 of porcelain or other suitable insulating material. Within this core is arranged a central electrode 3, projecting beyond the inner end of the core in the form of a spark point 4, and projecting beyond the outer end of the core in the form of a binding post 5. The electrode 3 is secured in position by means of a retaining nut 6, and a clamping nut 7 is provided upon the binding post for clamping thereto a wire conductor in the usual way.

The core 2 is inclosed within an outer shell or casing composed of sections 8 and 9, said sections having a threaded connection 10 for detachably coupling them together, and the section 9 being provided with the usual externally threaded portion 11 to fit within the spark plug opening in

the engine cylinder, and also with an angular portion 12 for the application of a wrench or like tool whereby the spark plug may be screwed into and out of position. 60

Carried by the shell section 9 is an outer electrode 13 of substantially U-form, one of the parallel arms of which is fixed to said shell section and the other parallel arm of which forms a spark point 14 for co-operation with the spark point 4 of the electrode 3. These spark points 4 and 14 are spaced in the usual way to produce a spark gap 15. The core and shell sections are respectively formed with shoulders 16 and 17 between 70 which are clamped packing rings or gaskets 18, which form tight joints and adapt the core to be clamped rigidly to the outer shell in a firm and secure manner. The spark plug thus far described may be of a type 75 of construction in common use.

It is well known that as a result of the sparking action wear occurs upon both spark points of the electrodes, and that in addition the spark point of the outer electrode 80 is subject to wear and commonly becomes pitted through the action of the current crossing the spark gap. As a result the area of the spark point of the outer electrode is reduced and through this reduction of surface and coating of the spark point with carbon or other deposits the sparking action of the plug is impaired or such action entirely prevented.

In order to overcome this objection, I provide means whereby the electrodes may be relatively adjusted to compensate for pitting or other wear, as well as for variations in their position due to other causes, and I further provide means for increasing the 95 area of the outer electrode and keeping the same clean and free from carbon. For the purpose of enabling the electrodes to be relatively adjusted, I provide the core 2 with an eccentric surface 19, and the shell 100 section 8 with an eccentric bore 20, as best shown in Fig. 2, such surfaces being eccentric to the bore of the core through which the electrode 3 extends. By this means it is evident that by turning or rotating the core 105 in one direction or the other within the sleeve and then fixing it to the sleeve against relative movement, the electrode 3 will be adjusted eccentrically with relation to the point 14 of the electrode 13, so that different 110 portions of the surface of the point 4 may be presented at intervals to the surface of the

point 14 as required in service, enabling new surfaces of the points 4 and 14 to be brought into operative position after the surface in use has become pitted or otherwise worn.

5 Fitted upon the inner arm forming the point of the electrode 13 is a cap or sleeve 21, which is preferably provided with a closed end 22, forming its sparking surface, the opposite end of said cap being open to adapt 10 it to be fitted in position upon the point 14, as will be readily understood. The closed end of this cap normally rests upon the free end of the point 14 and forms the sparking surface of the electrode 13, which is spaced 15 from the point 4 to produce the requisite size of spark gap 15. The cap 21 is made of conducting material and increases the sparking area of the electrode 13, and as this cap is free to slide back and forth upon the 20 point 14, toward and from the point 14, a carbon removing or cleansing action is thereby set up. It will be understood that when the engine piston is on its exhaust or compression stroke the pressure of the gases 25 on the cap or sleeve 21 will force it upwardly on the point 14 toward the point 4, while upon the suction or firing stroke of the piston the cap 21 will drop or move in the opposite direction by gravity and the 30 suction force of the piston. In this manner the cap will be reciprocated, thus keeping all surfaces clean and free from carbon or other deposits.

Having thus fully described my invention, 35 I claim:

1. A spark plug including a shell or cas-

ing having a bore eccentric to the axis thereof, a core of cylindrical form in cross section rotatably mounted in said bore, a stationary electrode carried by the shell or 40 casing, a central electrode carried by the core, said central electrode being arranged axially of the core and said electrodes being in axial alinement with each other and at all times a fixed distance apart, the construction being such that by rotary adjustments of the core in the eccentric bore the central electrode may be adjusted to bring different portions of the electrodes into coacting relation. 45

2. A spark plug including a shell or casing, a core mounted therein, a stationary electrode carried by the shell or casing and having a portion disposed longitudinally in the plane of the axis of the core, a central 55 electrode carried by the core in axial alinement with said portion of the stationary electrode, and a cap loosely mounted upon said portion of the stationary electrode for reciprocating motion thereon toward and 60 from the central electrode and adapted to engage the contact end of the latter.

3. A spark plug including the usual upper and lower spaced electrodes, a cylindrical member closed at one end loosely engaged 65 over the said lower electrode and adapted to slide thereon, the said cap being a conductor and adapted when moved upwardly to have its closed end engage with the end of the upper electrode. 70

In testimony whereof I affix my signature.
WILSON HOUSMAN.
